United States Patent Office

Des. 183,242
Patented July 22, 1958

183,242

MOTOR COACH

Clarence V. Crockett, Bloomfield Hills, and Roland E. Gegoux, Pontiac, Mich., assignors to General Motors Corporation, Detroit, Mich., a corporation of Delaware

Application February 20, 1958, Serial No. 49,715

Term of patent 7 years

(Cl. D14—3)

Des. 183,242

PAGE 2

Fig. 4

Fig. 5

Figure 1 is a side elevational view of one side of a motor coach, showing our new design;

Figure 2 is a top plan view;

Figure 3 is a side elevational view of the other side of the motor coach;

Figure 4 is a front elevational view; and

Figure 5 is a rear elevational view.

The essential features of our design reside in those portions shown in full lines.

We claim:

The ornamental design for a motor coach, substantially as shown and described.
